UNITED STATES PATENT OFFICE.

SIDNEY MITCHELL, OF NEW YORK, N. Y.

CONTINUOUS PULP-BEATER.

1,380,920.

Specification of Letters Patent. Patented June 7, 1921.

Application filed August 23, 1919. Serial No. 319,347.

To all whom it may concern:

Be it known that I, SIDNEY MITCHELL, a citizen of the United States, residing at New York, in the county of New York and State 5 of New York, have invented certain new and useful Improvements in Continuous Pulp-Beaters; and I do hereby declare the following to be a full, clear, and exact description of the invention, such as will enable others 10 skilled in the art to which it appertains to make and use the same, reference being had to the accompanying drawings, and to characters of reference marked thereon, which form a part of this specification.

15 The present invention relates, generally, to improvements in pulp beating machines commonly employed in the paper manufacturing industry; and the invention has reference, more particularly, to an improved 20 construction of beater adapted to beat and tease out the fibers of the raw material to produce a proper pulp requisite to the carrying on of paper and straw board manufacture.

25 The invention has for its principal object to provide an improved and simplified construction of continuous pulp beating machine of the general type described in my prior Letters Patent dated September 3, 30 1918, and numbered 1,277,628.

The invention has for a further object to 35 provide an improved arrangement and construction of pulp separating screens or gratings through which the finished pulp passes, during the operation of the machine, to the discharge trough.

Other objects of the present invention, not at this time more particularly enumerated, will be clearly understood from the following 40 detailed description of the same.

The invention consists, primarily, in the novel construction of continuous beater hereinafter set forth; and the invention consists, furthermore, in the novel arrangements and 45 combinations of the various devices and parts, as well as in the details of the construction of the said parts, all of which will be hereinafter more fully described, and then finally embodied in the appended claims.

50 The invention is clearly illustrated in the accompanying drawings, in which:—

Figure 1 is a plan view of a pulp beater made according to and embodying the principles of my present invention, a portion 55 of the hood inclosing the beater roll being broken away.

Fig. 2 is a vertical longitudinal section of the same, taken on line 2—2 in said Fig. 1.

Fig. 3 is a vertical transverse section of the same, taken on line 3—3 in said Fig. 2. 60

Fig. 4 is a detail view of the main separating screen or grating, drawn on an enlarged scale, and the same being shown in partial longitudinal section.

Fig. 5 is a detail transverse section taken 65 on line 5—5 in Fig. 4, drawn on a further enlarged scale.

Fig. 6 is a detail transverse section of one 70 of the secondary screens or gratings, drawn on an enlarged scale.

Similar characters of reference are employed in all of the hereinabove described views, to indicate corresponding parts.

Referring now to said drawings, the reference character 1 indicates the usual beater 75 tub in which the beater mechanism and the novel separating devices are mounted, and in which the raw material to be pulped, and the water for softening the same and assisting its circulation around the tub to the 80 beater roll, is deposited. Arranged within the tub is the usual mid-feather 2 which terminates short of each end of the tub, and which serves to properly divide the tub to provide the desired continuous circulatory 85 passage therein. Mounted between one side wall of said tub and said mid-feather 2 is the usual beater roll 3, having a series of radially projecting fly-bars 4 on its circumference. A transversely journaled driving 90 shaft 5 is mounted in connection with said tub upon which the roll 3 is fixed, said shaft being provided with a suitable belt pulley 6, or other suitable means for driving the same. Arranged beneath said beater roll 3 95 is any desired form of base-plate 7, with which the beater roll co-operates in beating out the raw material into the required pulp. Extending over the exposed portion of the beater roll 3 is an inclosing hood 8, having 100 a portion substantially concentric to the circumference of the beater roll, and in the forward end of which is provided a transverse discharge opening 9. Arranged exteriorly 105 in front of and beneath said discharge opening 9 is a discharge trough or conduit 10 which may extend in slight downwardly sloping inclination to and beyond either side of the tub 1 as may be desired.

Secured within said hood 8, so as to extend between the side walls of the latter, and so as to be positioned within and at the

upper end of said discharge opening 9, is a transverse supporting member 11, preferably in the form of a rod or pipe. The main separating screen or grating is comprised 5 of a series of rods or bars 12 suspended from said supporting member 11, so as to extend perpendicularly downward across the said discharge opening 9. Preferably said rods or bars 12 are spaced apart so as to 10 provide a series of narrow intermediate interstices 13, which under ordinary conditions may be from one-quarter to one-half inch in width. Said rods or bars 12 may be either secured to said supporting members 15 so as to be either rigidly related thereto or capable of a limited vibratory swing or oscillation from their point of attachment to said supporting member, although I prefer the latter method of mounting the same, 20 since the slight vibration or movement permitted by such mounting tends to more easily and quickly dislodge unmasticated or insufficiently pulped portions of raw material which may be flung against the bars, 25 and consequently provides a better assurance against clogging of the intermediate interstices 13. I have shown in the drawings, and more particularly in Figs. 4 and 5, one method of securing the rods 12 to the 30 supporting member 11. This method consists in providing each rod with a tail-piece 14 which is inserted through openings 15 in said supporting member 11, after which the upwardly projecting end of the tail-piece is 35 provided with a head 16, by riveting over the same, or in any other desired manner. If vibratory play is to be allowed to the rods, the openings of the supporting member 11 are made slightly larger in diameter than 40 the diameter of the tail-piece 14.

Secured within said hood 8 intermediate said above-described main grating or screen and the beater roll 3 are one or more auxiliary or secondary gratings or screens, each 45 comprising a transverse supporting member 17 to which are secured a series of rigidly depending bars or rods 18, the latter being more widely spaced apart than are the bars 12 of the main screen or grating, so as to 50 provide relatively wider intermediate interstices 19. The lower free ends of said bars or rods 18 are curved outwardly away from the beater roll 3 so as to assure against any possible contact of the fly-bars 4 of the 55 roll therewith, which might result in injury to either the former or the latter.

In operating the device the tub 1 is filled with water and the raw material to be pulped is deposited therein. The beater 60 roll 3 is then set in motion. The rotation of the beater roll acts as a paddle upon the water in the tub, causing the same to circulate around the tub in the path defined by the walls of the tub and the mid-feather 2.

The circulatory flow of the water thus set 65 up carries the raw material between the beater roll and the base-plate 7 in the usual manner, thereby causing the reduction of the raw material into a fibrous mass, which with the water in which it is carried produces the pulp desired. The nature of the raw material is such that almost immediately some portions thereof are reduced to the necessary pulpy mass, while other portions, being more resistant, are not so reduced until during the circulation through the tub they are carried many times into contact with the beater roll. During the operation of the beater the properly reduced or pulped portions of the raw material are, 75 in a large part, separated from the more resistant mass and discharged continuously from the hood ready for use, leaving the more resistant mass for further treatment, until it too is gradually reduced and discharged. This separation is effected as follows: During the rotation of the beater roll 3 a certain amount of water and pulped raw material is carried around with the same, the pulp being thrown outwardly by centrifugal force from the circumference of the beater roll. The outwardly precipitated portions of pulp are thrown toward the auxiliary or secondary screens or gratings, and thereupon pass through the comparatively widely spaced interstices 19 between the rods or bars 18 thereof, and are thence thrown against the main grating or screen formed by the relatively closely spaced bars or rods 12. If any raw material not properly 85 reduced, strings, or other non-pulped material are thrown off by the beater roll 3, the same are in most instances caught by one or the other of the said auxiliary or secondary screens or gratings, and held back 90 until, under the action of gravity, they drop back into the tub for further circulation and mastication therein. Such pulped material as passes the auxiliary or secondary screens is thrown against the main screen 95 or grating, and if properly reduced to a fine enough condition, passes through the interstices of the same, and thence through the discharge opening 9 so as to fall into the discharge trough 10, being thence 100 discharged from the beater machine. Such material as is still too coarse to pass through the interstices of said main screen or grating, and which is consequently not sufficiently reduced or pulped to be fit for discharge 105 from the beater, is lodged upon the bars or rods 12 and held back, soon falling by gravity back into the tub 1 for further treatment. In my former patent I provided means for flooding water over the 110 main screen or grating, so that the unpulped material lodged thereon would be thereby aided in slipping down by gravity 115 120 125

and away from the screen to fall back into the tub. With the type of screen comprised of diagonally disposed bars the flooding water constituted a materially assisting agency in cleansing the screen, I find however, that when the screen rods are substantially perpendicular, as in the present herein described construction, the additional supply of flooding water may be dispensed with, since enough water is thrown upon the screens by centrifugal force from the rotating beater roll in company with the pulped material to maintain the screen in sufficiently wetted down condition to assure the quick and requisite falling or slipping down of insufficiently pulped material under the pull of gravity, thus greatly simplifying and cheapening the construction of the beater. I also find that the bars 12 of the main screen will readily clear themselves of the un-pulped material even though they are rigidly secured, although not quite so rapidly as when said rods are permitted to oscillate or vibrate slightly under the impact of the outwardly flying pulp, therefore, generically, I consider the present invention to include a screen in which the rod elements are either rigidly fixed or free to vibrate slightly. I have made the further discovery that, when the rods are permitted to vibrate or oscillate in connection with their supporting means, a more rapid clearing of un-pulped material is effected, if the rods are movable independently of each other, rather than movable in fixed groups as in my aforesaid earlier patent. In some classes of work the auxiliary or secondary screens may be dispensed with, the main screen serving sufficiently to cause the due separation of pulped and un-pulped material. All the above-mentioned advantages are the result of the simplified construction illustrated and described in this application, and then finally set forth in the appended claims.

My present construction of beater is continuous in operation, and consequently as the raw material is reduced in quantity by discharge from the beater in the form of properly pulped material, additional quantities of raw material may be deposited in the tub from time to time without necessity of stopping the beater, or of interrupting the pulping and continuous discharging action of the same.

I am aware that some changes may be made in the general arrangements and combinations of the devices and parts, as well as in the details of the construction of the same, without departing from the scope of my present invention as described in the foregoing specification, and as defined in the claims appended hereto. Hence, I do not limit my invention to the exact arrangements and combinations of the devices and

parts as set forth in the foregoing specification, nor do I confine myself to the exact details of the construction of said parts as illustrated in the accompanying drawings.

I claim:

1. In a device of the kind described, a tub; a beater roll therein; a hood inclosing said beater roll having a discharge opening therein, a grating comprised of closely spaced rods interposed between said discharge opening and said beater roll, and a discharge trough exteriorly arranged relative to said discharge opening to receive pulp discharged through said grating by centrifugal force from said beater roll.

2. In a device of the kind described, a tub; a beater roll therein; a hood inclosing said beater roll having a discharge opening therein; a grating interposed between said discharge opening and said beater roll, said grating comprising a series of substantially perpendicular rods spaced apart to provide intermediate narrow interstices, and means for supporting said rods; and a discharge trough exteriorly arranged relative to said discharge opening to receive pulp discharged through said grating by centrifugal force from said beater roll.

3. In a device of the kind described, a tub; a beater roll therein; a hood inclosing said beater roll having a discharge opening therein; a transverse supporting member fixed in said hood in the rear of said discharge opening, a series of depending closely spaced rods attached to said supporting member to extend downwardly across the area of said discharge opening forward of said beater roll, means for connecting said rods with said supporting member so that each rod is capable of an independent oscillatory movement relative to said supporting member, and a discharge trough exteriorly arranged relative to said discharge opening to receive pulp discharged through the intervening spaces between said rods by centrifugal force from said beater roll.

4. In a device of the kind described, a tub; a beater roll therein; a hood inclosing said beater roll having a discharge opening therein; a grating interposed between said discharge opening and said beater roll, said grating comprising a series of substantially perpendicular rods spaced apart to provide intermediate narrow interstices, means for supporting said rods so that each rod is capable of an independent oscillatory movement, and a discharge trough exteriorly arranged relative to said discharge opening.

5. In a device of the kind described, a tub; a beater roll therein; a hood inclosing said beater roll having a discharge opening therein; a grating interposed between said discharge opening and said beater roll, said grating comprising a series of substan-

tially perpendicular rods spaced apart to provide intermediate narrow interstices, means for supporting said rods so that each rod is capable of an independent oscillatory movement, an auxiliary grating comprising a series of substantially perpendicular rods spaced more widely apart, means for supporting said latter rods between said first mentioned grating and said beater roll, and

a discharge trough exteriorly arranged relative to said discharge opening. 10

In testimony that I claim the invention set forth above I have hereunto set my hand this 20th day of August, 1919.

SIDNEY MITCHELL.
